HEATING APPARATUS

Emil Blaha, Cheltenham, Pa., assignor to Selas Corporation of America, Philadelphia, Pa., a corporation of Pennsylvania

Application April 18, 1946, Serial No. 663,158

18 Claims. (Cl. 25—142)

1

My invention relates to heating apparatus, such as furnaces, kilns, and ovens, for example. While the principles of the invention may be employed for a variety of heating purposes, both industrial and otherwise, the improvements disclosed herein are especially useful in those heating applications in which consideration must be given to the character of the atmosphere enveloping the work being heated, especially the presence of objectionable and undesirable constituents in the gases forming such work enveloping atmosphere.

In view of the fact that the character of the atmosphere enveloping the work often is an important factor in many heating operations it has usually been the practice in such cases, when a combustible gas mixture is utilized as a source of heat, to employ internally fired heat radiating muffles or tubes to keep the work or goods out of physical contact with the high temperature heating gases consisting of heated products of combustion. In this way the heating chamber is fired to an elevated temperature by heat radiated from the exterior surfaces of the muffles, and a gaseous atmosphere is provided which is of such a character that it will contribute to produce the desired end result in the goods or work being fired.

Such heating practices have been followed, for example, in the firing of articles to produce glazed or glass-like surfaces, as in the glost firing of ceramic ware and in vitreous enamelling. This is so because the high temperature heated products of combustion usually contain harmful constituents, such as sulphur dioxide and sulphuric acid fumes, for example, which adversely affect the glazed surfaces produced on articles when such heated gases freely circulate in the atmosphere enveloping the work.

In accordance with the present invention, it is proposed to heat work to high temperatures in heating chambers by radiant heat in such a manner that the character of the atmosphere enveloping the work may be accurately determined while projecting such radiant heat from a plurality of heat radiating regions which are heated to incandescence by a high temperature gaseous heat producing medium exposed to the chamber atmosphere. I accomplish this by withdrawing exteriorly of the heating chamber the gaseous heat producing medium before such medium can pass into the heating chamber and become an active component of the chamber atmosphere.

In order to produce high radiant heating temperatures, the heat radiating regions are preferably heated to incandescence by combustion of a combustible gas mixture effected at vicinities or zones adjacent to such regions and in open communication with the heating chamber. The heated gases generated and developed at the combustion vicinities or zones adjacent to the heat radiating regions may be withdrawn therefrom at

2

such a rate that the chamber atmosphere is substantially free of objectionable and undesirable components. Thus, in practicing the invention to produce glazed or glass-like surfaces on articles, the heated products of combustion may be withdrawn exteriorly of the chamber at such a rate from the combustion vicinities that the chamber atmosphere is impoverished in sulphur impurities to such a degree that the glazed or glass-like surfaces produced are smooth and lustrous and free of surface defects.

By effecting combustion of the gas mixture at vicinities or zones adjacent to heat radiating regions to heat such regions to incandescence, such combustion vicinities or zones being in open communication with the heating chamber, radiant heat is projected from the regions without the necessity of shielding the work or goods from the combustion zones by a heat transfer wall or barrier like a muffle. In this way radiant heat transfer may be accomplished at the highest possible temperature from the heat radiating regions which are heated to a high incandescent condition and openly exposed to the heating chamber at the surfaces adjacent to which burning of the gas mixture is accomplished.

In the embodiment of the invention disclosed herein the heated gases generated and developed at the combustion zones or vicinities are withdrawn and diverted therefrom, without becoming an active component of the chamber atmosphere, by producing a suction effect adjacent to the combustion vicinities. Such suction effect may be produced by an exhaust blower to cause withdrawal of the high temperature heated gases exteriorly of the heating chamber through a path of flow which is in heat exchange relation with a wall of the heating chamber. To promote further the radiant heating of work in the heating chamber, the path of flow through which the diverted heated gases pass exteriorly of the heating chamber may be formed of refractory material which is heated to incandescence and from the outer surfaces of which heat is radiated to the interior of the heating chamber.

The suction effect produced adjacent to the combustion vicinities may be adjusted to effect withdrawal of the heated gases from the vicinities at such a rate that heated gases can pass substantially by diffusion only from the combustion vicinities into the chamber atmosphere. Under such conditions the gases at the boundaries or interfaces between the heated gases formed at the combustion vicinities and the chamber atmosphere may be maintained practically quiescent.

In practicing the invention the pressure in the heating chamber may be slightly below the pressure of the surroundings and negative due to the suction effect produced adjacent to the vicinities at which combustion is accomplished. Such suction effect may be utilized to draw into the heating chamber an essential gas which con-

tributes to the end result desired when firing work at high temperatures. In the firing of articles to produce glazed or glass-like surfaces thereon, for example, the negative pressure of the heating chamber may be utilized to draw essential air into the chamber which purges the gases in the chamber and contributes to the production of high quality glazed surfaces on work.

Further, in a continuous tunnel type furnace or kiln having preheating and cooling zones at the opposite ends of a high temperature firing zone embodying the invention, the essential air may be drawn into the high temperature zone through the cooling zone into which the work passes after being fired to the desired high temperature. In this way, the heated work in cooling gives up heat to essential air in the cooling zone, and such preheated air is then introduced into the firing zone to effect purging of the gases therein.

Due to the suction effect produced adjacent to the vicinities at which combustion is accomplished, there will always be a tendency for gases of the chamber atmosphere to be drawn exteriorly of the kiln or furnace along with the diverted heated products of combustion before such heated products can become an active component of the furnace atmosphere. Suitable control provisions may be provided to control the inflow of essential air into the heating chamber, the rate of withdrawal of the heated products of combustion, and the pressure and rate at which the combustible gas mixture is supplied to the vicinities at which combustion is accomplished. Some or all of these variable factors may be controlled, for example, responsive to a temperature condition affected by the temperature maintained in the heating chamber.

The novel features which I believe to be characteristic of my invention are set forth with particularity in the claims. The invention, both as to organization and method, together with the objects and advantages thereof, will be better understood by reference to the following description taken in connection with the accompanying drawings, of which:

Figs. 1 and 2 are longitudinal horizontal and vertical sectional views, respectively, illustrating more or less diagrammatically a preheating zone and a portion of an intermediate high temperature firing zone of a continuous tunnel kiln embodying the invention;

Figs. 1A and 2A are longitudinal horizontal and vertical sectional views, respectively, diagrammatically illustrating another portion of the intermediate high temperature firing zone and cooling zone of the kiln shown in Figs. 1 and 2;

Fig. 3 is an enlarged transverse vertical sectional view, taken at line 3—3 of Fig. 1, to illustrate the high temperature firing zone more clearly;

Fig. 4 is an enlarged fragmentary transverse vertical sectional view, taken at line 4—4 of Fig. 5, to illustrate details of the high temperature firing zone;

Fig. 5 is an enlarged fragmentary longitudinal sectional view, taken at line 5—5 of Fig. 1, to illustrate more clearly the side walls of adjacent portions of the preheating and high temperature firing zone, respectively;

Fig. 6 is an enlarged fragmentary horizontal sectional view, taken at line 6—6 of Fig. 3, to illustrate more clearly the burners and flues

therefore embodied in the high temperature firing zone;

Fig. 7 is an enlarged front view of a refractory shape, partly broken away and in section, to illustrate details of the burners embodied in the high temperature firing zone;

Fig. 8 is an exploded perspective view of the refractory shape of Fig. 7;

Fig. 9 is an enlarged transverse vertical sectional view, taken at line 9—9 of Fig. 1, to illustrate the preheating zone more clearly;

Fig. 10 is an enlarged transverse vertical sectional view, taken at line 10—10 of Fig. 1A, to illustrate details of first and second portions of the cooling zone of the continuous tunnel kiln;

Fig. 11 is an enlarged vertical sectional view, taken at line 11—11 of Fig. 1A, to illustrate more clearly the final and last portion of the cooling zone;

Fig. 12 is a horizontal plan view of the continuous tunnel kiln of Figs. 1 to 11 and control provisions for the kiln; and

Fig. 13 is a view diagrammatically illustrating the operating conditions existing at the combustion vicinities adjacent to the refractory lined heat radiating regions distributed along the high temperature firing zone.

In the drawings the instant invention has been shown in connection with a continuous tunnel kiln 14 through which goods or wares may be moved successively through a preheating zone or section 15, a high temperature firing zone or section 16 and a cooling zone or section 17. It is to be understood that the kiln 14 is only illustrative of one manner of practicing the invention for producing glazed or glass-like surfaces on articles, and that the improvements disclosed herein may be embodied in other forms of heating apparatus.

The goods or wares to be treated are loaded on kiln cars 18, as shown in Figs. 3, 9, 10 and 11, which are moved slowly through the kiln chamber on a track 19. Each kiln car 18 includes a superstructure providing spaced apart transverse passages 20 at the underside of a platform 21 upon which the goods or wares, diagrammatically indicated by the dotted line 22, are loaded in any conventional manner.

refractory body portion of each car 18, which 50 is carried by a metallic underframe, extends through an opening or slot formed in the bottom wall of the kiln chamber. In this way narrow gaps 23 are formed between the sides of the refractory body portions of the cars 18 and the 55 side walls of the slot, the lower ends of each are closed and sealed at 24 by flanges which extend downwardly from the sides of the cars 18 into troughs adapted to contain sand or like material. During operation of the kiln 14, the cars 18 moving through the kiln chamber are in abutting relation and the gaps 23 are effectively sealed at the lower ends thereof longitudinally of the kiln, as just explained, so as to minimize leakage of air into the kiln chamber.

After the goods or wares to be treated are loaded on the cars 18, such cars are moved in succession onto a transfer track 25, as best shown in Fig. 1, on which the cars pass into a side entrance vestibule 26 having a normally closed sliding door 27. The vestibule 26 is located at the inlet end of the preheating zone 15, and vestibule propeller mechanism 28 of any well known type, having a reciprocating pusher member 29, may be provided to move the cars 18 slowly through the kiln chamber. As shown in Fig. 1A, the cars 18 discharged

from the cooling zone 17 of the kiln chamber pass into an exit vestibule 30 from which the cars are moved through a normally closed sliding door 31 onto a transfer track 32.

The sides of the kiln 14 are provided with suitable supporting framework 33 connected at the upper ends by cross rods 34. The framework 33 extends the full length of the kiln and includes metallic side walls 35 forming an outer shell for the kiln 14. As best shown in Fig. 3, the refractory kiln structure providing the high temperature firing zone or section 16, which is disposed within the framework 33 and outer metallic side walls 35, includes spaced apart side walls 36, a roof 37, and a bottom 38 having the slot or opening therein through which the refractory body portions of the cars 18 project, as previously explained.

In the refractory side walls 36 of the high temperature firing zone or section 16 are mounted or incorporated gas-fired radiant heaters or burners 40 each having a cavity 41 at an inner face thereof opening into the kiln chamber. Each radiant heater comprises a molded block 42 of ceramic material having a central passage within which is disposed a tube or sleeve 43 of refractory material. As best shown in Figs. 3 and 6, the tubes or sleeves 43 extend rearwardly from the block 42 through wells or openings 44 formed in the outer portions of the refractory side walls 36. The extreme outer ends of the tubes 43 may be connected by suitable flexible connections to apertured brackets 45 fixed to the casing 35, as seen in Fig. 3. The tubes or sleeves 43 may also be spring-biased at the brackets in any suitable manner (not shown), so as to cause the rear enlarged portion of each tube to fit snugly in position at the rear face of the block 42 with which it is associated.

The heater tubes 43 are connected by pipes 46 to short horizontal manifolds 47 which in turn are connected by conduits 48 to larger vertically disposed headers 49. The combustible gas mixture is delivered to the headers 49 from a suitable source of supply in any desired manner. In the conduits 48 are connected manually operable valves 50 to control the pressure and rate at which the gas mixture is supplied to each horizontal manifold 47, and in the pipe connections 46 are provided manually operable valves 51 for individually controlling the support of the gas mixture to each radiant heater 40.

The inner end of each tube or sleeve 43 adjacent to the heater cavity 41 is internally threaded to receive an exteriorly threaded part of a gas distributor tip 52 formed of refractory material. The gas mixture in the tubes 43 is subdivided into a plurality of gas streams by a plurality of slots or channels 53 formed about the periphery of and extending lengthwise of the narrow part of the distributor tip 52. The outlet ends of the channels 53 at the underside of the enlarged end of the tips 52 flare outwardly toward the inner wall surfaces 54 of the heater cavities 41.

The gas mixture is discharged from the outlet ends of the channels 53 at the undersides of the enlarged ends of the tips 52, and it is at these regions that the flames are produced and maintained. The individual flames produced at the tips 52 flare outwardly and project into the cavities or spaces 41 alongside of the outwardly flaring wall surfaces 54. The gas flames maintained at the tips 52 effect such heating of the inner wall surfaces 54 that the latter are heated to incandescence.

The gas mixture introduced into the spaces or cavities 41 is subjected to the intense radiant heat of the inner wall surfaces 54, so that substantially complete burning of the gas mixture may be accomplished in the spaces or cavities before the heated gases pass from the open ends of the spaces 41. By providing the radiant heaters 40 a large fraction of the heat developed and generated in the spaces 41 is converted to radiant heat which is projected from the highly incandescent wall surfaces 54 into the interior of the high temperature firing zone 16 to effect heating of the goods or wares passing therethrough on the cars 18.

15 The heated gases generated and developed at the vicinities of the radiant heaters 40 pass into spaced apart vertical flues 55 in the refractory side walls 36, as will be explained more fully hereinafter. As shown in Fig. 5, the lower ends of the vertical flues 55 communicate with horizontal flues 56 provided in the firing zone at the bottom parts of the refractory side walls 36. The ends of the horizontal flues 56 terminating at the juncture of the firing zone 16 and cooling zone 17 are closed, and the opposite ends terminating at the juncture of the firing zone 16 and preheating zone 15 communicate with the horizontal transverse passages 57 formed in the bottom parts of a pilaster 58.

20 As shown in Fig. 5, the lower ends of vertical flues 59, which are offset laterally with respect to the horizontal flues 56 in the firing zone 16, communicate with the transverse passages 57. Each side of the refractory kiln structure 25 at the pilaster 58 is formed with openings or passages 60 at different levels which communicate with the vertical flues 59 and through which heated gases may flow into horizontal heat transfer flues 61 extending lengthwise of the preheating zone 15 at each side wall of the kiln chamber 40 from the pilaster 58 to the entrance vestibule 26. The horizontal flues 61 extending lengthwise of the preheating zone 15 and into which the heated gases pass through the openings 60 from the vertical flues 59 are disposed one above the other in the refractory side walls of the kiln, as shown in Fig. 9.

25 The horizontal flues 61 comprise a plurality of rows of refractory shapes or tiles 62 in abutting relation and secured together, as by a high-temperature cement, for example. The refractory shapes 62 are U-shaped in section and disposed one above the other so that the longer closed sides thereof are substantially in alignment to provide heat radiating surfaces at the side walls of the kiln chamber substantially coextensive in height with the maximum vertical loading of the goods or wares on the cars 18. The shorter legs of the refractory shapes 62 cooperate with refractory 30 brick of the kiln structure to form the longitudinally extending passages or flues 61. The refractory shapes 62 are preferably formed of a refractory material having good thermal conducting properties, such as silicon carbide, for example, to promote heat transfer from the heated gases through the inside walls of the flues 61 to the goods or wares passing through the preheating section 15.

35 The flues 61 in the preheating zone 15 communicate with vertical flues 63 and 64 formed in the kiln side walls adjacent to the entrance vestibule 26, as best shown in Fig. 1. To the upper ends of the vertical flues 63 and 64 are connected ducts 65 and 66, as shown in Fig. 9, which 40 in turn are connected by a duct 67 to the inlet

of an exhaust blower 68 which may be driven in any suitable manner, as by an electric motor, for example.

It will now be seen that the residual heat in the heated gases passing into the horizontal flues 61 of the preheating zone 15 is effectively utilized to effect preheating of the goods moving through such zone to the high temperature firing zone 16, and that the gases are thereafter discharged exteriorly of the kiln 14 by the exhaust blower 68. 10

After the goods or wares are treated in the high temperature firing zone 16, such goods then pass into the cooling zone 17 in which the temperature of the goods is gradually reduced. As shown in the left-hand part of Fig. 10, the portion 15 of the cooling zone 17 immediately adjacent to the firing zone 16 is formed with relatively thick refractory side walls 69 spaced from the metallic side walls 35 of the outer casing to provide vertically extending passages 70 therebetween. At 20 the first portion of the cooling zone adjacent to the firing zone 16, the bottom edges of the metallic side walls 35 terminate a short distance from the extreme lower ends of the kiln side walls 69 to provide openings 71 through which air from the surroundings may pass upwardly through the passages 70. Heat is given up by the refractory side walls 69 to the air passing upwardly through the passages 70, thereby promoting natural draft circulation of air over the outer surfaces of the kiln side wall 69, as indicated by the arrows in the left hand part of Fig. 10, to effect initial cooling of the treated goods passing from the firing zone 16.

The second or intermediate portion of the cooling zone 17 is shown in the right hand part of Fig. 10 and differs from the first portion just described in that vertical passages 72 are formed within the refractory side walls 73. The thickness of the refractory side wall separating the kiln chamber and each passage 72 is considerably less in the second or intermediate portion of the cooling zone 17 than in the first portion thereof, so that the temperature of the goods will be reduced further in the second portion by the natural draft circulation of air which enters the lower ends of the passages at inlets 74.

As shown in Fig. 11, the final and last portion of the cooling zone 17 is formed by hollow metallic shells 75 and 76 defining the roof and side walls, respectively, of the kiln chamber at the exit end thereof. Air to effect the final cooling of the goods or wares may be circulated through the shells 75 and 76 in counterflow to the movement of the goods toward the exit vestibule 30, as shown in Figs. 1A and 11. This may be accomplished by introducing air into the shell 75 through suitable openings (not shown) formed in the end thereof adjacent to the exit vestibule 30. Air may also be introduced into the shells 76 through suitable conduit connections 77 provided at the bottom parts thereof adjacent to the exit vestibule 30. The cooling air is withdrawn from the shells 75 and 76, at regions removed 65 from the exit vestibule 30, through conduits 78, 79 and 80, which are connected by a conduit 81 to the inlet of an exhaust blower 82, as shown in Fig. 11.

By providing the cooling zone 17 just described, 70 the temperature of the treated goods can be reduced in several stages without adversely affecting the goods, so that the goods will be at a desired low temperature upon reaching the exit vestibule 30 to be discharged from the kiln 14.

It has been explained above that the radiant heaters 40 in the high temperature firing zone 16 are heated to a high incandescent temperature by a gaseous heat producing medium. By accomplishing a large part and preferably substantially all of the combustion of the gas mixture in the vicinities or spaces 41 adjacent to the wall surfaces 54 of the radiant heaters 40, extremely high combustion temperatures are developed to heat the wall surfaces to a highly radiant condition. In this manner a large proportion or fraction of the heat developed and generated in the spaces 41 is converted to radiant heat which is projected from the highly incandescent wall surfaces 54 into the interior of the high temperature firing zone 16 to effect heating of the goods or wares passing therethrough on the cars 18.

In accordance with the present invention, in order to control the character of the atmosphere in the high temperature firing zone 18, the heated gases generated and developed in the combustion spaces or vicinities 41 are withdrawn exteriorly of the kiln 14 before such heated gases can become an active component of the atmosphere enveloping the work in the high temperature firing zone. In the embodiment of the invention disclosed herein, this is accomplished by positioning at the open end of each combustion space or cavity 41 a plate 83 having an opening therein 25 of approximately the same size as the cavity opening. Each plate 83 is spaced a short distance from a lip 84 formed at the front face of the ceramic body 42 about the cavity opening, so as 30 to form a gap 85 between the plate 83 and the front face of the block 42.

The gaps 85 serve as outlets for the combustion spaces or cavities 41 through which the heated gases are withdrawn and diverted before passing outwardly through the open ends of the cavities. The diverted gases pass through the gaps 85 into the vertical flues 55 which are closed 40 at the upper ends and communicate at the lower ends with the larger horizontal flues 56, as described above.

Since the exhaust blower 68 is connected to withdraw gases from the horizontal flues 61 in the preheating zone 15 and the latter are arranged to receive heated gases from the horizontal flues 56 in the firing zone 16, a suction effect may be produced in the horizontal flues 56 and vertical flues 55 which is reflected back to the gaps 85. The plate 83 of each radiant heater 40 is positioned relatively close to the forward edge of the lip 84 defining the extreme open end of the cavity 41, so that restricted outlets are provided by the gaps 85 at which regions the suction effect produced by the blower 68 is intensified in a manner similar to the suction effect produced at the nozzle of a vacuum cleaner. Since the blocks 42 are subjected to elevated temperatures as high as 2800° F. and higher at the inner faces thereof, the plates 83 must not only withstand thermal shock but provision must be made for holding such plates accurately in position under all of the operating conditions of the kiln 14.

To this end each refractory block 42 is constructed in such a manner that the plate 83 associated therewith forms a rigidly held part of the block. As shown most clearly in Fig. 8, each block 42 comprises a refractory shape having slots or channels 86 extending lengthwise of the shape at the cut-away corners thereof. The slots or channels 86 are more or less U-shaped in cross section and formed with outwardly flaring side

walls to receive tie rods 87 having enlarged end portions 88. The slots 86 are deeper at the front and rear ends than at the intermediate portion, as shown in Figs. 7 and 8, to receive the enlarged ends 88 of the tie rods 87.

The tie rods 87, which are more or less triangular-shaped in section, are firmly secured in position in the slots 86, as by high-temperature cement, for example. When the tie rods are secured in position, the refractory shape and tie rods embodied therein form the rectangular-shaped block 42 having smooth outer surfaces at the four sides thereof to facilitate mounting each such block in the side walls 36 of the high temperature firing zone 16.

The enlarged forward ends 88 of the tie rods 87 are notched at the inner faces thereof, as indicated at 89, to receive the cut-away corners of the apertured plate 83. The notches 89 accurately position the plates 83 a fixed distance from the lips or raised portions 84 at the front faces of the burner blocks 42, the plates being secured in position in any suitable manner, as by high-temperature cement.

As seen in Figs. 5 and 6, the radiant heaters 40 are in spaced apart relation in the side walls 36 and arranged in vertical rows. The refractory blocks 42 are mounted at the inner portions of the refractory side walls 36 between vertical rows of refractory blocks 90 which are of less depth than the blocks 42, as best shown in Fig. 6. Refractory plates 91 are arranged between adjacent vertical rows of radiant heaters 40, the outer vertical edge portions of which bear against the plates 83 fixed to the refractory blocks 42. The refractory plates 91 are disposed one above the other in vertical rows and cooperate with the refractory blocks 90 to form vertically extending spaces between adjacent vertical rows of radiant burners 40.

The refractory plates 91 are T-shaped in section, as shown in Fig. 6, and the blocks 90 are formed with relatively deep slots to receive the rearwardly extending legs 92 of such plates. In this manner the vertical spaces in front of the blocks 90 are divided to form two manifolds or flues 55 each of which communicates with the gaps 85 in one vertical row of radiant heaters 40. Thus, for each vertical row of radiant heaters 40, the heated gases generated and developed in the spaces or cavities 41 can be withdrawn through the gaps 85 into the vertical flues 55 provided at both sides of the heaters.

By producing a suction effect in the vertical flues 55 in the firing zone 16 which is intensified at the gaps 85, the pressure at the gaps is below and negative with respect to the pressure prevailing in the combustion spaces or vicinities 41 of the radiant heaters 40. By providing any well known control provisions, such as a damper 93 in the conduit 67 which is connected to the inlet of the exhaust blower 68, as shown in Fig. 9, the suction effect produced at the gaps 85 may be adjusted and controlled. Hence, substantially all or any desired fraction of the heated gases generated in the combustion spaces 41 can be effectively withdrawn from said spaces and diverted through the gaps, as diagrammatically indicated by the arrows F in Fig. 13, before such gases can pass from the combustion spaces 41 through the open ends thereof and become an active component or constituent of the atmosphere in the firing zone 16.

The suction effect produced at the gaps 85 of the radiant heaters 40 is related to the pressure

at which the gas mixture is supplied to the heaters and the lengths of the individual flames produced in the combustion spaces 41. In the operation of the radiant heaters 40, as indicated more or less diagrammatically in Fig. 13, the inner cones of different size flames A¹, A², and A³ always extend more or less along an axis B alongside of the inner wall surface 54. Irrespective of the lengths of the flames, the inner cones thereof will always be out of contact with the wall surface 54.

When the radiant heaters 40 are being operated at low capacity and the flames are relatively small, the suction effect produced at the gaps 85 is correspondingly adjusted so as to avoid pulling the flames from the wall surface 54 and reducing the effectiveness of the flames in heating the refractory linings of the heaters to a high incandescent temperature. When the pressure at which the gas mixture is supplied to the radiant heaters is increased, the suction effect produced at the gaps 85 may also be correspondingly increased.

In radiant heaters of the type illustrated, there is a tendency for the individual flames to bend inwardly toward the axes of the heaters in a manner similar to the bending of the ribs of an umbrella when it is fully opened. It has been found that the suction effect produced at the gaps 85, which completely encircles the open ends of the combustion spaces 41, tends to overcome such lifting of the individual flames from the wall surfaces 54 and promote uniform incandescent heating of the wall surfaces. It has also been observed that when the radiant heaters 40 are being operated at less than maximum capacity, the areas of the wall surfaces 54 heated to incandescence increases when the suction effect is produced at the gaps 85 to withdraw and divert heated gases into the vertical flues 55.

The gas mixture supplied to the radiant heaters 40 may be a complete mixture in which all of the combustion supporting gas, such as air, for example, is supplied with the combustible gas to effect substantially complete combustion of the latter in the combustion spaces or vicinities 41. Under these conditions the suction effect produced at the gaps 85 may be regulated to withdraw and divert through the gaps substantially all of the heated gases generated and developed in the combustion spaces, so as to maintain the regions at the open ends of the spaces 41 practically quiescent. When such operation of the radiant heaters 40 is effected, no blast of heated gases can be felt by the hand when it is momentarily placed over the open ends of the combustion spaces 41. When the suction effect produced at the gaps 85 is regulated so as to maintain the gases immediately in front of the open combustion spaces practically quiescent, heated gases can pass substantially by diffusion only from the spaces 41 into the interior of the high temperature firing zone 16.

The suction effect produced at the gaps 85 also may be regulated to minimize the flow of the heated gases by diffusion from the open ends of the spaces 41. This may be accomplished by producing a suction effect to reduce the pressure in gaps 85 below the pressures prevailing in the spaces 41 and the regions adjacent to the open ends thereof, which is of such magnitude as to produce a substantial inflow of the atmosphere gases from the firing zone 16 into the open ends of the spaces 41, as indicated by the arrows C 75 in Fig. 13. Such atmosphere gases drawn into

the open ends of the spaces 41 pass toward the gaps 85 and flow therethrough, along with the diverted heated gases, in a common stream into the vertical flues 55. It is to be understood that there will always be a tendency for gases in the atmosphere of the firing zone 16 to be drawn into the open ends of the spaces 41 due to the suction effect produced at the gaps 85. When a complete gas mixture is supplied to the radiant heaters 40, the suction effect is preferably properly related to the gas pressure delivery pressure to effect substantially complete combustion of the gas mixture in the spaces or vicinities 41 of the radiant heaters 40.

In firing the high temperature zone 16, the gas mixture supplied to the radiant heaters 40 may be a partial mixture and some of the air to accomplish complete burning of the combustible gas may be drawn into the spaces or vicinities 41 by the suction pressure produced at the gaps 85. The admission of air into the firing zone 16 may be due to leakage or may be positively controlled, as will presently be pointed out. Any air passing into the firing zone is heated therein and, due to such preheating, is capable of producing higher combustion temperatures at the radiant heaters 40 when drawn into the spaces 41 thereof.

Inward movement of the heated air into the spaces or vicinities 41 of the radiant heaters 40 is promoted due to the pressure conditions prevailing in the combustion spaces. There is a low pressure region at the central parts of the spaces 41, adjacent to the enlarged ends of the distributor tips 52, into which gases tend to be drawn, as indicated diagrammatically by the arrows D in Fig. 13. Since the suction effect produced at the gaps 85 is strongest at the peripheries of the spaces 41 and weakest at the central regions thereof, an adequate flow of heated gases containing air may be induced at the central regions of the spaces, as indicated diagrammatically by the arrows E in Fig. 13, which supply part of the combustion supporting gas to effect combustion of the combustible gas supplied in a partial mixture to the spaces 41.

The kiln 14 is especially useful in treating work to produce glazed surfaces thereon, as in the glost firing of ceramic ware and in vitreous enamelling, for example. Such work can be fired in the firing zone 16 to high temperatures by radiant heat projected from the radiant heaters 40, without the necessity of shielding the work by a heat transfer wall of an internally fired muffle or tube, so that radiant heat transfer can be effected at high temperatures from the combustion spaces or vicinities 41 whose wall surfaces are heated to the highest possible temperature.

If no provision were made for diverting and withdrawing through the gaps 85 the heated gases generated in the combustion spaces 41, such heated gases could pass into the firing zone 16 and the objectionable constituents in such gases, such as sulphur dioxide and sulphuric acid fumes, for example, would adversely affect the glazed or glass-like surfaces produced on the work being treated. However, in firing work in the high temperature zone 16, the character of the atmosphere enveloping the work can be controlled by producing the requisite suction effect at the gaps 85, whereby heated gases can pass by diffusion only from the spaces 41 into the firing zone 16. Since the rate at which the heated gases can pass by diffusion into the atmos-

sphere of the firing zone 16 is relatively low, the extent to which objectionable constituents or impurities are carried into the firing zone atmosphere is extremely small and insufficient to adversely affect the smooth and lustrous glazed surfaces produced on work.

During operation of the kiln 14, the sliding doors 27 and 31, at the entrance and exit vestibules 26 and 30, respectively, are normally kept closed and opened only for the purpose of admitting cars 18 into the entrance vestibule and removing such cars from the exit vestibule. The pilaster or wall section 58 between the pre-heating zone 15 and the firing zone 16 forms a constriction in the kiln chamber whereby objectionable drift or movement of the gases between these kiln sections is minimized. A similar pilaster or wall section 94 may be provided at the juncture of the firing zone 16 and the cooling zone 17, as shown in Figs. 1A and 2A. The gaps 23 between the cars 18 and sides of the slot at the bottom of the kiln 14 are sealed at 24 by the train of cars 18 moving through the kiln chamber in abutting relation, as previously explained. By providing the normally closed doors at the entrance and exit vestibules, the pilasters 58 and 94 at each end of the firing zone 16, and the sealing provisions 24 at the sides of the cars 18, the circulation of gases in the atmosphere enveloping the work being treated in the firing zone 16 is minimized which contributes to the production of high quality glazed surfaces on work. Under these conditions the firing zone 16 is filled with gases which are impoverished in sulphur impurities.

By providing a kiln like the kiln 14 which is relatively gas-tight, that is, a kiln structure into which the leakage of air into the kiln chamber is at a minimum, the pressure in the firing zone 16 may be maintained slightly below atmospheric pressure due to the suction effect produced at the gaps 85. Such operation of the kiln 14 differs from the usual furnace or kiln operation in which the gaseous atmosphere is at a positive pressure 45 and slightly above that of atmospheric. The fact that the firing zone 16 may be maintained at a pressure slightly below atmospheric can be advantageously utilized to promote purging of gases in the firing zone 16, as will be pointed out presently.

It is to be understood that in a continuous tunnel kiln like that disclosed herein, it is not possible to seal the firing zone 16 completely and the necessary care must be taken to keep air leakage into the kiln chamber to a minimum. When the extent to which air leaks into the kiln chamber increases, the suction effect produced at the gaps 85 may be increased to overcome the adverse affect such air may have in tending to reduce the high incandescent temperatures to which the radiant heaters 40 are heated.

When work is being treated in the high temperature firing zone 16, the atmosphere therein is desirably oxidizing. In such case air admitted 65 into the firing zone 16 purges the gases in the atmosphere enveloping the work being treated and also contributes to the production of high quality glazed surfaces on the work. Such air, which may be referred to as "essential air," may 70 pass into the firing zone or section 16 by leakage in the normal operation of the kiln. However, such leakage of air into the firing zone 16 should not be excessive because any air over and above that necessary to effect the desired end 75 result, may be referred to as "unessential air."

because such air causes an undesirable drop in temperature in the firing zone 16 and does not serve any useful purpose.

In the kiln 14 of the invention the admission therein of essential air, when an oxidizing atmosphere is desired, may be effectively controlled. Such an arrangement is diagrammatically shown in Fig. 12 wherein an air admission conduit 95 is provided in vestibule 30, for example. A suitable damper 96, which may be manually controlled, if desired, may be provided in the conduit 95 for controlling the rate at which air is admitted into the cooling zone 17 of the kiln chamber. By providing a kiln structure which is reasonably air-tight, the pressure in the firing zone 16 may be maintained slightly below atmospheric pressure so as to cause movement of air through the conduit 95 into the cooling zone 17 and through the latter into the firing zone 16 to purge the gases therein.

Such controlled movement of air through the cooling zone 17 to the firing zone 16 serves several useful purposes. First, the air in passing through the cooling zone effects cooling of the treated goods or wares therein and, in so doing, gradually becomes heated. Second, such heated air in entering the firing zone 16 effects purging of the gases and does not exercise any undesirable cooling effect in the firing zone. Third, when a partial combustible gas mixture is supplied to the radiant heaters 40, and gases from the atmosphere in the firing zone 16 are drawn into the spaces 41 to supply any deficiency in the combustion supporting gas to promote complete combustion in the spaces 41, the oxidizing gases of the firing zone atmosphere drawn into the spaces 41 will be at an elevated temperature, thereby promoting higher combustion temperatures at the radiant heaters 40.

The admission of air through the conduit 95 into the kiln chamber may be automatically controlled, if desired, responsive to the temperature of the firing zone 16. Moreover, such control of the rate at which air is admitted into the kiln 14 may be associated with suitable control provisions for regulating the supply of the combustible gas mixture to the radiant heaters 40 and the suction pressure produced at the gaps 85. As shown in Fig. 12, this may be accomplished by providing a control system including a thermo-couple 97 arranged within the firing zone 16 so as to be subjected to the high temperatures produced therein. The thermo-couple is connected by conductors 98 to a suitable potentiometer control 99 of any well known and conventional type which is connected by conductors 100 to a source of electrical energy. The potentiometer control 99 may be connected by conductors 101 and 102 to suitable control devices 103 and 104, such as servo-motors, for example, operatively associated with the dampers 93 and 96, respectively. The potentiometer control 99 may also be connected by conductors 105 to control devices 106 each of which is operatively associated with a valve 107 provided in a conduit 108 through which the combustible gas mixture is supplied to the radiant heaters 40 at one of the side walls 36 of the firing zone.

In the firing of articles in the high temperatures zone 16 to produce glazed surfaces thereon, the control system just described is so adjusted that the rate of flow of the gas mixture through the main supply conduits 108 to the radiant heaters 40 is controlled by the valves 107 responsive to the temperature in the firing zone

16, such control being effected by the thermo-couple 97, potentiometer control 99 and control devices 106 operatively associated with the valves. In this manner the desired high temperature may be maintained in the firing zone 16, the flow of the gas mixture supplied to the radiant heaters increasing and decreasing when the temperature decreases and increases, respectively, from the desired high temperature.

10 The damper 93 in conduit 87 is similarly controlled through the potentiometer control 99 and control device 103 operatively associated therewith and increases and decreases the suction pressure at the gaps 85 with increase and decrease, respectively, in pressure at which the gas mixture is supplied to the radiant heaters 40.

15 The damper 96 in conduit 95 for controlling the admission of air into the cooling zone 17 may be also regulated through the potentiometer 99 and control device 104 operatively associated therewith, whereby the desired admission of air into the firing zone 16 may be regulated to maintain a suitable oxidizing atmosphere in the latter. When the suction effect produced at the

20 gaps 85 increases and decreases, the valve 95 moves toward and from its closed position, respectively, so that essential air only is supplied to the firing zone 16 to purge the gases therein, as previously explained. It is to be understood, however, that the damper 96 may be manually controlled so that it will not be influenced by the temperature in the firing zone 16.

25 The vertical flues 55 associated with the radiant heaters 40 are preferably of such size that the paths of flow for the diverted heated gases will be adequate to withdraw practically all of such heated gases generated and developed in the combustion spaces 41 when the heaters are being operated at maximum capacity. Further,

30 the vertical flues 55 are considerably larger in cross-section than the gaps 85, so that heated gases will pass at a lower velocity through the vertical flues and give up heat to the side walls 36 in which they are incorporated and also to

35 the work through the flue walls formed by the plates 91. In the event any unburned gases are withdrawn and diverted from the spaces 41 through the gaps 85 into the flues 55, combustion of such gases may be completed in the vertical flues because the cover plates 91 become heated to an incandescent temperature which is above the ignition temperature of the combustible gas. Under such conditions, the flues 55 serve as heat radiating muffles and contribute to the heating

40 of work in the firing zone 16.

45 When a combustible gas mixture of ordinary city gas and air is supplied to the radiant heaters 40, such gas having a rating of about 550 B. t. u. per cubic foot, the heat radiating regions or wall surfaces 54 may be heated to a temperature of 2800° F. and higher and are at a high thermal head for treating work passing through the firing zone 16. The cover plates 93 for the radiant heaters are also heated to a high incandescent temperature which may be in the neighborhood of about 2500° F. and at a thermal head slightly below the wall surfaces 54 of the combustion spaces 41. The plates 91 for the

50 vertical flues 55 are also heated to incandescence and are at a lower thermal head which may be from about 50° to 100° F. higher than the temperature of the atmosphere in the firing zone 16.

55 In view of the high temperatures produced at the cover plates 93, such cover plates and the

tie rods 87 of the refractory blocks 42 are preferably formed of a refractory material, such as silicon carbide, for example, which is capable of holding up under extremely high temperatures without developing cracks and also possesses high tensile strength and resistance to thermal shock. The refractory plates 91 for the vertical flues 55 also may be formed of refractory material consisting entirely or preponderantly of silicon carbide. Since heat transfer is effected from the heated gases passing through the vertical flues 55 through the cover plates 91 to the interior of the firing zone 16, it is desirable to provide cover plates 91 formed of refractory material possessing good thermal conductive properties.

The refractory bodies 42 of the radiant heaters 40 may be formed of mullite or any other suitable refractory material having poor thermal conductive properties, so that the wall surfaces 54 of the combustion spaces 41 at the front faces of the blocks 42 can be effectively heated to the highest possible temperatures. The tie rods 87 effectively hold the refractory block 42 together when the inner faces thereof are heated to a highly radiant condition and stresses are induced in the blocks due to the rear parts remaining relatively cool while the regions adjacent to and at the inner surface 54 are heated to high temperatures.

The tie rods 87 not only serve to increase the life of the refractory blocks 42 but also maintain the apertured plates 83 accurately positioned a short distance from the raised lips 84 at the front faces of the blocks. The tie rods 87 of high tensile strength tend to retard cracks developing in the refractory bodies 42 and also tend to retard the growth of cracks after they have once occurred. Further, when the refractory bodies 42 are subjected to repeated thermal shock over a long interval of time, the tie rods effectively hold such blocks together and prevent any part being dislodged.

In order to promote uniform heating of the goods or wares when the cars 18 pass through the kiln chamber from the preheating zone 15 into the high temperature firing zone 16, only a single radiant heater 40 is provided at the refractory side walls 36, adjacent to the bottom 38 at the extreme inlet end of the firing zone 16, as shown in Figs. 2 and 5. Adjacent to such single radiant heater 40 in each refractory side wall 36 are provided two radiant heaters 40 one above the other. All of the remaining vertical rows of radiant heaters 40 in the side walls 36, throughout the entire length of the firing zone, include three radiant heaters 40 disposed one above the other. With this arrangement of the radiant heaters 40 in the side walls of the firing zone 16, the temperature of the work is increased more uniformly to the requisite high temperature at which it is desired to fire the work in the firing zone 16. It is to be understood however, that the radiant heaters may be distributed along the refractory side walls 36 in any desired manner to produce the requisite heating curve during movement of the work through the firing zone.

It has previously been explained that the heated gases passing upwardly in the vertical flues 59 at the inlet end of the firing zone 16 are subdivided by the passages 60 through which the heated gases pass into the horizontal heat transfer flues 61 in the preheating zone 15. Due to the natural draft or flue effect in the vertical flues 59, there is a tendency for the heated gases

to be distributed unequally between the horizontal flues 61 in each kiln side wall, so that each bottom horizontal flue 61 receives less than its proportionate share of the heated gases.

In order to compensate for this unequal division of the heated gases flowing through the horizontal flues 61, a row of gas-fired radiant heaters 109 are incorporated in the bottom part of each side wall of the preheating zone 15, at a portion thereof adjacent to the firing zone 16, as shown in Figs. 1, 2 and 9. The radiant heaters 109 comprise burner blocks, similar to the burner blocks 42 in the firing zone 16, which are mounted in the kiln side walls directly at the rear of the refractory shapes or tiles 62 forming the bottom horizontal flues 61. The combustible gas mixture supplied to the radiant heaters 109 is subdivided by distributor tips 110 to produce a plurality of flames to heat the inner surfaces of the radiant heaters to a high incandescent temperature.

The refractory shapes 62 at the bottom horizontal flues 61 are heated by the heaters 109 by both radiant and convection heating components and the heated gases generated and developed by such heaters mixes with the heated gases entering the bottom horizontal flues from the firing section 16. Hence, the heaters 109 increase the heating accomplished by the bottom horizontal flues 109 over and above that effected by the heated gases passing therethrough from the vertical flues 59. In this way more effective heat transfer is accomplished through the inner walls of the bottom horizontal flues 61, thereby compensating for the unequal division of the gas passing therethrough from the firing zone 16 and promoting more uniform heating of work in the preheating zone 15 in which there is also a tendency for the heated gases to rise into the upper part thereof.

While the exhaust blower 68 has been provided to produce a suction effect at the gaps 85 of the radiant heaters 40 in the firing section 16, it will be understood that such suction effect may be produced in any other well known manner, such as, for example, by a steam or air ejector.

In the embodiment of the invention shown and described, the size of the opening or aperture in the plate 83 of each radiant heater is suitably related to the opening in the cavity 41 at the rim 84, so that the heated gases will be effectively withdrawn from the cavity when a suction effect is produced at the gap 85. This is accomplished in the radiant heaters 40 by providing apertures in the plates 83 which are slightly less in diameter than the extreme open ends of the burner cavities 41, as seen in Fig. 6.

Attention is called to my copending application Serial No. 663,157, filed concurrently herewith, which is directed to the construction of the burner which is used in the kiln wall hereof and attention is also called to my copending application Serial No. 663,159, which was filed concurrently herewith and which is directed to a method of firing a kiln and which has become Patent 2,474,301.

Although I have shown and described a single embodiment of the invention, it will be obvious to those skilled in the art that modifications and changes may be made without departing from the spirit and scope of the invention. Thus, other forms of radiant heaters than the radiant heaters 40 disclosed herein may be employed in which the heat radiating regions are heated to incandescence by a gaseous heat producing medium. Also, the principles of the invention may be

applied equally well to other forms of heating apparatus, such as furnaces or ovens, for example. I therefore aim in the following claims to cover all modifications and changes which fall within the true spirit and scope of the invention.

What is claimed is:

1. In a continuous tunnel kiln including a pre-heating section, an intermediate high temperature firing section and a cooling section having an elongated kiln chamber extending therethrough, a plurality of refractory lined radiant heaters distributed along the firing section; means to supply a high temperature gaseous fuel adjacent to said radiant heaters at vicinities in open communication with the kiln chamber at the firing section to heat said heaters to incandescence for radiating heat therefrom into the chamber; passage means providing vertically disposed passages in the side walls of the firing section which communicate with the vicinities adjacent to said radiant heaters, horizontally disposed passages in the walls of the firing section which communicate with the vertical passages, and horizontal passages in the preheating section communicating with the horizontal passages in the firing section; and means including an exhaust blower connected to the horizontal passages in the preheating section to produce a suction effect in the passages for diverting from the vicinities into the passages and withdrawing therethrough the burned gaseous fuel tending to pass from the vicinities into the kiln chamber at the firing section before such medium becomes an active component of the atmosphere in the firing section; at least the walls of the vertical passages in the firing section and the walls of the horizontal passages in the preheating section forming inner wall surfaces of the firing and preheating sections, respectively.

2. In a continuous tunnel kiln including a pre-heating section, an intermediate firing section and a cooling section having an elongated kiln chamber extending therethrough, heat radiating means for the firing section of the kiln chamber, means for heating said radiating means to incandescence by combustion of a gaseous fuel exposed to the kiln chamber atmosphere at the firing section, conduit means for supplying the gaseous fuel to effect heating of said radiating means, exhaust means including structure providing passages for withdrawing exteriorly of the kiln a substantial fraction of the heated gases developed by said combustion before such gases become a component of the chamber atmosphere at the firing section, said structure being formed to provide at least a portion of said passages in said preheating section, said cooling section having an inlet for air at a region removed from the firing section, temperature responsive regulating means for controlling the supply of the gaseous fuel through said conduit means, means associated with said regulating means for controlling the rate of withdrawal of the heated gases by said exhaust means, and means for controlling the flow of air through the inlet into said cooling section.

3. In a continuous tunnel kiln including a pre-heating section, an intermediate firing section and a cooling section having an elongated kiln chamber extending therethrough, heat radiating means for the firing section of the kiln chamber, means for heating said radiating means to incandescence by combustion of a gaseous fuel exposed to the kiln chamber atmosphere at the firing section, exhaust means including structure

providing flue passages for withdrawing exteriorly of the kiln a substantial fraction of the heated gases developed by said combustion before such gases become a component of the chamber atmosphere at the firing section, said structure being formed to provide a vertical flue passage in each side wall of the kiln at regions adjacent to the juncture of the preheating and firing sections through which upward flow of the heated gases is effected, and a plurality of horizontal flue passages extending longitudinally of the preheating section at the side walls thereof, said horizontal flue passages in each side wall of the preheating section being disposed one above the other and connected to receive heated gases from one of the vertical flues, said horizontal flues being effective to promote heating in said preheating section of the kiln chamber, and means for increasing the heating accomplished by the bottom horizontal flue passages over and above that effected by the heating gases passing therethrough from the vertical flue passages.

4. The combination set forth in claim 3 in which said means for increasing the heating accomplished by the bottom flue passages comprises burners disposed within the flue passages.

5. The combination set forth in claim 3 in which said means for increasing the heating accomplished by the bottom horizontal flue passages comprises gas-fired burners of a radiant type disposed within the flue passages.

6. The combination set forth in claim 3, in which the horizontal flue passages in the preheating section have refractory walls forming the inner wall surfaces of the preheating section of the kiln chamber, and said means for increasing the heating accomplished by the bottom flue passages comprising gas-fired radiant heat elements disposed therein from which radiant heat is adapted to be projected against the refractory walls forming said inner wall surfaces.

7. In a kiln having a chamber, means forming a heat producing wall for said chamber including a series of members provided with surfaces adapted to radiate heat directly to said chamber, supply means for a fuel adapted to be burned adjacent said surfaces and thereby heat said surfaces to incandescence, additional members forming passages in said wall, said first-mentioned members including means forming paths between said passages and surfaces whereby products of combustion may be removed from said surfaces through said paths to said passages, and means to apply a suction effect to said passages so products of combustion may be removed from said surfaces prior to the time they reach said furnace chamber.

8. In a kiln having a chamber, means forming a heat producing wall for said chamber including a plurality of members, each member having a cavity formed therein facing said chamber, mechanism to supply a fuel to be burned adjacent the surfaces of said cavities to heat them to incandescence and thereby direct radiant heat into said chamber, means forming a plurality of passageways in said wall adjacent said cavities, means forming restricted paths of flow between the edges of said cavities and said passageways, mechanism to apply a suction effect to said passageways and paths to withdraw the products of combustion from said cavities before they mingle with the atmosphere of said chamber whereby said chamber is heated by radiation from said cavities.

9. In a kiln having a chamber, a heat producing wall for said chamber including a plurality of refractory blocks each having a cavity formed therein, means to mount said blocks in rows with the cavities facing said chamber, a plurality of furnace wall members, means to mount said members in rows between said blocks, said members and the means to mount them cooperating to form passageways between each row of blocks, means to form restricted paths of flow between the edges of each of said cavities and said passageways, and means to apply a pressure to said passageways that is less than the pressure in the furnace chamber.

10. In a kiln having a chamber, refractory members forming the walls of said chamber, refractory burner blocks located in rows in said walls, said blocks each being formed with a cavity open into said chamber, means to supply a fuel to be burned in said cavities to heat the same and thereby produce radiant heat to be projected directly into said chamber, refractory parts attached to said wall between said blocks and cooperating with said wall to form passageways with said parts facing said chamber, said passageways being formed with openings extending to the edges of said cavities, and means to draw the products of combustion from said cavities through said openings into said passageways before said products of combustion can enter said chamber, said parts being heated by said products of combustion so that they also supply radiant heat to said chamber.

11. In a kiln having a chamber, a wall for said chamber including refractory structure forming rows of radiant heat emitting surfaces, said structure including passageways extending in said wall between said rows of surfaces and an additional passage connecting said passageways, said passageways being provided with an opening adjacent the edge of each radiant heat emitting surface that they pass, means to supply a fuel to be burned closely adjacent said surfaces to heat the same, and means to withdraw the products of combustion through said openings into said passageways and passage before they can get into said chamber, said products of combustion serving to heat the walls of said passageways so that they also radiate heat to said chamber.

12. In a kiln having a chamber, a wall for said chamber including structure providing alternate rows of radiant heat emitting burners open to said furnace chamber and passageways, said passageways being provided with openings extending adjacent the edges and slightly in front of the burners which lie alongside them, means to supply fuel to be burned in said burners to heat the same, and means to withdraw the products of combustion from said burners through said openings and passageways before said products of combustion can enter said kiln chamber.

13. In a kiln having a chamber in which ware is fired, a wall for said chamber including alternate rows of radiant burners each provided with a radiant heating cavity opening directly into said chamber and rows of passageways extending in a vertical direction between said burners, said passageways being provided with portions thereof extending to the edges of said cavities, means to supply a fuel to said burners to be burnt in said cavities to heat the surfaces of the same and thereby radiate heat directly to said chamber, and means to withdraw the hot products

of combustion from said cavities through said passageways before said hot products of combustion can enter said kiln chamber, said hot products of combustion heating the walls of said passageways so that the latter will supply additional radiant heat to said kiln chamber.

14. The combination of claim 13 including means responsive to the temperature of said kiln chamber, means to adjust said supply means and thereby regulate the amount of fuel supplied to said burners, and mechanism operative in accordance with the responses of said responsive means to operate said means to adjust.

15. In a kiln having a firing zone, means forming a heat producing wall for said zone including a plurality of radiant heaters each provided with a cavity opening directly into said zone, means to supply fuel to be burned closely adjacent the surfaces of said cavities to thereby heat the same to incandescence, refractory members forming passageways extending between said burners and along said wall, means cooperating with said members and said burners to form restricted paths of flow between the edges of said cavities and said passageways through which products of combustion may flow from said cavities to said passageways, and means to withdraw the products of combustion from said cavities through said passageways before said products of combustion can enter into said firing zone.

16. The combination of claim 15 including means responsive to the temperature of said firing zone, and mechanism operative in accordance with the responses of said means to regulate said means to supply fuel.

17. The combination of claim 15 including means to supply a desired gas to said firing zone, said gas being withdrawn therefrom through said passageways by said means to withdraw along with said products of combustion.

18. The combination of claim 15 including means responsive to the temperature of said firing zone, means to control the supply of fuel to said heaters, means to control the flow of products of combustion to said means to withdraw, and mechanism operative in accordance with the responses of said temperature responsive means to coordinate the operation of said two control means.
